UNITED STATES PATENT OFFICE.

MAURICE GALIBERT, OF NEW YORK, N. Y.

ADHESIVE LABEL.

1,295,300.

Specification of Letters Patent. Patented Feb. 25, 1919.

Application filed November 5, 1918. Serial No. 261,224.

To all whom it may concern:

Be it known that I, MAURICE GALIBERT, a citizen of the United States, residing in the city, county, and State of New York, have invented certain new and useful Improvements in Adhesive Labels, of which the following is a specification.

This invention relates to a label for a labeled container having an exterior shou-
10 dered surface; its object being to effect the labeling in such wise that paper or other temperable labels will be molded into conformity with the contour of the exterior wall of such containers, and not be partially loose thereon presenting a partially wrinkled and accordingly unsightly appearance, as has often been the case in prior practice.
15 While my method is of particular utility in the mechanical labeling of tubular con-
20 tainers having at each end an exterior flanged cap the inward edge of each flange forming an exterior peripheral shoulder or collar on the container, yet my method may be worked either mechanically or manually
25 on any shape of container having an exterior shoulder which increases its cross-sec-
tional dimension.

In the accompanying drawings, forming a part hereof and illustrating the principle 30 of this invention in the best mode now known to me of applying that principle,

Figure 1 is a lengthwise central section of an unlabeled tubular container each end of which is provided with a cupped cap the 35 flange of which is exterior to the outward surface of the tubular body of the container.

Fig. 2 shows the back side of a paper label gummed in accordance with my invention.

Fig. 3 shows the capped container of Fig. 40 1 labeled in accordance with this invention.

Referring to the drawings, 1 is a tubular container body, each end of which is covered by a cupped cap 2, the flange 3 of which encircles the container body and constitutes a 45 peripheral shoulder or collar thereon, whereby the container surface to be labeled has relative high and low surfaces.

The back of my new gummed or adhesively attachable paper label 4 is provided 50 either before or during the labeling operation, when there are two exterior cap shoulders on the container, with two opposed marginal gum strips 5, extending in the direction of the wrapping length of the label 55 from end to end thereof, as shown. Inwardly of and adjacent each such marginal

gum strip 5, the label back is provided with an ungummed space 6 parallel to a gum strip 5; and between the two gumless spaces 6, the label back is covered with an intermediate strip 7 of gum of the full wrapping length of the label. By strip, in this connection, is meant a surface made adhesive by any suitable material whether applied, allowed to set and subsequently put into an adhesive condition; or applied moist as the label is being applied.

The point respecting the marginal strip or strips 5 is that the gum or adhesive is made liquid enough to "temper" the margin or 70 margins of the labels,—that is to soften and render them stretchable. The point respecting the intermediate gum strip 7 is preferably that the gum or adhesive shall be less liquid, that is of heavier body which will in 75 practice only negligibly temper the paper on which it is applied. In actual practice, a thick adhesive is used for the gum strip 7, but it is not intended to limit the invention to non-tempering of the paper correspond- 80 ing to such strip because actual tempering of such portion of the paper might be successfully practised. The purpose of the two parallel gumless spaces 6 is to afford clean, 85 gumless surfaces on the label back for contact with mechanical labeling instrumentalities so that the latter will not become gummed. The importance of this is known to all skilled in the labeling machine art.

The width of each marginal gum strip or 90 strips is approximately correspondent to the width of a shoulder or collar or flange of the

container, thereby preferably to be adhesively attached not only to the peripheral

surface of the collar, shoulder or flange, but 95

also the inward edge thereof; and when the

tempered and so stretchable margin or mar-

gins of the label are applied on the shoul-

der or shoulders, the label widthwise can be

by suitable pressure molded to fit the con-

tour of the container, the intermediate more

tenacious gum or adhesive on strip 7 holding

the label to the body of the container while

the stretchable paper margins tempered by

the more liquid gum strips 5 are confined to 105

the cap flanges or shoulder-forming collars.

The result is that the body of the label be-

tween the collars or cap or cover flanges is

laid smooth on the container body; and com-

pared with all machine-labeled containers 110

known to me presents a much neater and

more desirable appearance, the more or less

wrinkled appearance of such labels of such prior container being eliminated. In such prior practice, the labels have been smooth and tight around the shoulder-forming collars or cap or cover flanges, and more or less loose and wrinkled between them.

Containers labeled by the described labels and by the present method are easily recognizable both by the smooth adhesion of the 10 body of the label between the end collars, and also, on examination, by the presence of the two gumless spaces 6, two of which are in the nature of mechanical features whether there is more than one gummed strip 5 or 15 not; and by the relation of the gummed strip 7 to one or more gumless spaces 6 and one or more gum strips 5.

So far as I now know, this invention finds 20 its main and perhaps exclusive utility in the application of paper labels, but the invention is susceptible of use in connection with any flexible label which has a temperable margin or margins. By gum is meant any suitable adhesive whether of gum proper, 25 paste, or otherwise. The word temper is extensively and commonly used in the paper label and paper working arts to indicate softening and consequent stretchability, and

the elements, liquidity of the adhesive and time, enter into it.

The method of procedure herein described forms the subject-matter of my co-pending application Serial No. 261,225, and the labeled or wrapped container herein described forms the subject-matter of my co-pending application Serial No. 261,223, both filed November 5, 1918.

What I claim herein is:

1. The herein - described partially tempered label provided with a marginal adhesive strip on a temperable margin; with two parallel non-adhesive portions spaced apart and parallel to the adhesive, tempered margin; and with an adhesive surface between such non-adhesive portions.

2. The herein - described partially - tempered label or wrapper provided with a marginal adhesive strip on a temperable margin; with an adhesive surface adjacent but spaced away from the marginal adhesive strip; and with a non-adhesive portion intermediate the marginal adhesive strip and said adhesive surface.

In testimony whereof I have hereunto set my hand this 31st day of October, 1918.

MAURICE GALIBERT.
